UNITED STATES PATENT OFFICE.

FLORENCE L. GRIFFEN, OF BROOKLYN, NEW YORK, ASSIGNOR TO REVERE RUBBER COMPANY, OF CHELSEA, MASSACHUSETTS, A CORPORATION OF RHODE ISLAND.

DESIGN FOR A BATHING CAP.

Application filed July 2, 1925. Serial No. 13,982. Term of patent 7 years.

To all whom it may concern:

Be it known that I, FLORENCE L. GRIFFEN, a citizen of the United States, residing in Brooklyn, county of Kings, and State of New York, have invented a new, original, and ornamental Design for Bathing Caps, of which the following is a specification, reference being had to the accompanying drawing, forming part thereof, wherein—

Figures 1 and 2 are side elevations of the opposite sides of a bathing cap viewed lying flat.

I claim:

The ornamental design for a bathing cap as shown. Signed at New York, in the county and State of New York, this 1st day of July, 1925.

FLORENCE L. GRIFFEN.
